Primary Examiner—T. Chase Nelson*Assistant Examiner*—Susan E Krakower(74) *Attorney, Agent, or Firm*—Ladas and Parry LLP(57) **CLAIM**

I claim the ornamental design for a food container, as shown and described.

DESCRIPTION

FIG. 1 is a top view of a food container according to my new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a perspective view of the food container in a disassembled condition with the top removed.

The broken lines illustrate unclaimed environmental structure.
